DESIGN FOR A COSMETIC CHART

Nathan Traub, Brooklyn, N. Y.

Application August 12, 1933. Serial No. 49,007

Term of patent 3½ years

To all whom it may concern:

Be it known that I, NATHAN TRAUB, a citizen of the United States of America, residing in Brooklyn, county of Kings, State of New York, have invented a new, original, and ornamental Design for a Cosmetic Chart, of which the following is a specification, reference being had to the accompanying drawing, forming part thereof.

Fig. 1 of the drawing is an elevational view of a cosmetic chart in closed position, showing my new design.

Fig. 2 is a diagrammatic showing in perspective of the pictures on the tab members shown in Fig. 1.

I claim:

The ornamental design for a cosmetic chart, as shown.

NATHAN TRAUB.
